Primary Examiner — Garth Rademaker*Assistant Examiner* — Laura H Yu*(74) Attorney, Agent, or Firm* — QuickPatents; Kevin Prince**CLAIM**

The ornamental design for a tape tag, as shown and described.

DESCRIPTION

FIG. 1 is a perspective view of a tape tag, showing my new design;

FIG. 2 is a front elevational view thereof;

FIG. 3 is a rear elevational view thereof;

FIG. 4 is a top plan view thereof, the bottom plan view being a mirror image thereof; and,

FIG. 5 is a left-side elevational view thereof, the right-side elevational view being a mirror image thereof.

The dot-dash broken lines represent a boundary of the design. The broken lines in the figures depict portions of the tape tag that form no part of the claimed design. The long-dash broken lines represent perforations, and form part of the claimed design.
